PHYSICIAN'S CABINET OR THE LIKE

Howell G. Evans, Two Rivers, Wis., assignor to
Hamilton Manufacturing Company, Two Rivers,
Wis., a corporation of Wisconsin

Application January 12, 1934, Serial No. 706,396

2 Claims. (Cl. 312—191)

This invention relates to physicians' cabinets or the like, and, among other objects, aims to provide an improved combined storage means for bottles and the like and a working top so disposed and arranged as to permit of ready access to the storage compartment, without movement of the bottles. Movement of the bottle support, as heretofore employed, to bring the bottles into position, is objectionable since it is apt to jar the bottles, frequently overturning them and shaking their contents.

It is desirable to have the bottles normally enclosed in the cabinet to guard against dust and breakage, and one object of my invention is to provide a simple and improved enclosure which is substantially dust-proof, and in which the movable members have a generally mating, flush, relationship, to avoid unnecessary projections or obstructions.

When opened, it is desirable that the bottle compartment constitute substantially a horizontal continuation of the working top of the cabinet so that the hands of the physician may move from the working top to the bottle compartment, and vice versa, substantially in a horizontal plane and without making it necessary for the physician to reach either up or down any appreciable extent for the bottles. The element of time heretofore involved in reaching up or down out of the normal plane of the working top of the cabinet is important in frequent moments in a physician's practice when the question of life or death may depend upon the saving or loss of a fraction of a second. At the same time, even when the cabinet is open, I provide means guarding against accidental displacement of the bottles.

With these and other objects in view, I will explain my invention more fully by reference to the attached drawing showing a preferred construction in which—

Figure 1 is a front elevation of the upper portion of my improved cabinet, showing the storage compartment open and with parts broken away for clarification;

Fig. 2 is an end elevational view taken from the left of the drawing, partly in section and showing the storage compartment open;

Fig. 3 is a similar view but showing the storage compartment closed; and

Fig. 4 is a fragmentary plan section taken on the line 4—4 of Fig. 1.

Referring in detail to the figures of the drawing, I have shown the upper portion only of my improved cabinet 10, it being understood that

the lower portion of this cabinet may be of conventional construction, containing the usual drawers, shelves, etc.

The cabinet 10 is provided with the working top 11 extending in a horizontal plane at the front of the cabinet 12. The working top 11 is advantageously surfaced with a suitable sanitary, stain-proof, material. My improved bottle-storage compartment, indicated generally by 13, is located to the rear of the working top 11 and advantageously extends substantially the entire length of the cabinet.

As here shown, the compartment 13 comprises a frame including a rear wall 14 which extends above the working top 11, and side walls 15, 16 extending at right angles to the rear wall 14 at each end of the cabinet. Desirably fixedly secured to the rear wall 14 is a long, flat support 17 extending horizontally within the space defined by the rear wall 14 and end walls 15, 16 but spaced from the side walls 15, 16 for a purpose presently pointed out. The support 17 may be conveniently attached to the rear wall 14 through the intermediation of a vertically extending spacing member 18, carried by the rear wall 14, to which the support 17 is secured as by means of a bracket 19, several of which may be employed, thus forming a cantilever connection with the rear wall, the support being otherwise unsecured.

Carried on the support 17 I have shown a sanitary tray 20 formed of hard, stain-proof material such as "Vitrolite," for example, which is removable from the support to be readily and thoroughly cleansed and sterilized when desired. The tray 20 may merely rest upon the support 17 and may have a high back 21 which abuts or is closely adjacent to the spacing member 18. The tray also desirably has a low retaining lip 22 along its front edge, and abutments 23 at each end. Thus the tray is adapted to receive and hold a plurality of bottles 24 in a row extending substantially the entire length of the cabinet. The tray also desirably terminates short of the end walls 15, 16.

A closure for my improved storage compartment 13 is provided in accordance with my invention, by the cover member 25 and the sliding wall or panel 26, interconnected by means of a system of levers, advantageously comprising levers in the nature of bell-cranks, whereby movement of one closure member causes movement of the other. In this instance, the cover member 25 is pivoted to each of the side walls 15, 16 as at 27, desirably so as, when closed (as shown in Fig. 3), 55

to be flush with the upper end of the rear wall 14. The rear wall 14 is desirably recessed as at 28 arcuately so that the rear edge 29 of the cover member 25 may be at all times in close proximity to the rear wall 14 so as to eliminate any unnecessary space between the cover member and the rear wall which would admit dirt or foreign objects. When open, as shown in Figs. 1 and 2, the rear edge of the cover member 25 rotates between the rear wall and the tray 20, to drop behind the rear wall 21 of the tray and so that the cover member becomes in effect a continuation of the spacing member 18.

Pivoted to the cover element 25 as at 30, in the present exemplary construction, is a link 31 which is articulated as at 32 with the shorter end of a main lever 33 pivoted at 34 upon the end wall 15, and between this wall and the support 17. The other or longer end of the main lever 33 is articulated as at 35 with a short link 36 which in turn is pivoted as at 37 upon the transverse vertical edge 38 of the sliding panel in a cut-away portion 38a in said edge. The side walls 15 and 16 are desirably grooved as at 39, 39 to receive the edges 38 of the sliding panel 26, which may also have the tongues 40 slidingly received in the deeper portions 41 of the grooves 39, thus providing tongue-and-groove guiding means for the sliding frame in its vertical reciprocatory movement, 30 caused by the pivoting of the lever 33.

As shown in Fig. 2, when the cover member 25 is raised, the longer end of the lever 33 is moved downwardly and the sliding panel 26 is automatically lowered upon its vertical track within the cabinet so that the bottles 24 are readily accessible and so that there is no obstruction between the working top 11 and the bottle-storage compartment 13. A demarkation between the working top and the storage compartment, however, is desirably well defined by the upper edge 42 of the sliding panel 26 which, in the open position of the parts, is not depressed below the working top 11, thus guarding against accidental displacement of the bottles. The panel 26, however, is depressed sufficiently to render the bottles readily accessible and to disclose the essential indicia or label on a bottle, as indicated at 43, so that the physician can perceive at a glance the respective contents of the bottles, all without movement of the bottles themselves. As best shown in Figs. 1 and 2, when the storage compartment is opened, the lever mechanism interconnecting the cover element and sliding panel is arranged to move freely in the space between the end of the tray 20 and the support 17 and the side wall of the cabinet, and in this open position, as best shown in Fig. 2, the lever mechanism is inconspicuous and offers no obstruction to ready access to the storage compartment.

60 So constructed and arranged the cover operating elements, as for example the panel 26 and the

lever mechanism, are disposed and move in the spaces between the cantilever support 17 and the side walls and working top.

As best shown in Fig. 3, when the storage compartment is closed, the upper edge 42 of the sliding panel 26, which is automatically elevated, desirably abuts the cover member 25 to provide a dust-proof closure.

It will be noted that I have shown two sets of the lever mechanisms, one at each end of the storage compartment 13, to enhance the smoothness, rapidity, and certainty of relative movement of the movable closure members 25 and 26. Since these lever mechanisms are alike, one description suffices for both.

15 Retaining members 44 and 45 secured to the support 17 and hooked around the tray 20 may be employed to retain the tray in position on the support, a pair at each end.

Obviously the invention is not limited to the details of construction shown for the purposes of illustration.

Having described my invention, I claim:

1. In a physician's cabinet or the like, the combination of a casing, a horizontally-extending working top on the casing, a rear wall for the casing spaced laterally from and extending above said working top, a horizontally-extending support for bottles or the like secured by a cantilever connection to the rear wall between the rear wall and the working top, and side walls extending at right angles to said rear wall and also extending above the working top, a cover member hinged to the casing in the vicinity of the upper extremity of the rear wall, said cover member adapted to be swung over the said support offset from the working top, a sliding panel interposed between the support and the working top adapted in one position to extend above the working top into abutment with the cover member and in another position to be depressed from the first position, and means interconnected with the cover member and sliding panel whereby movement of the cover member to open said cover member causes depression of the sliding member and the movement of the cover member to closed position causes elevation of the sliding member.

2. An article of manufacture for use as a combined storage and working cabinet of the class described, including the combination comprising a cabinet frame having rear and side walls, a working top surface carried on said side walls, said top surface terminating short of the rear wall, a support carried by the rear wall by a cantilever connection, said support being spaced from the working top and from the side walls, and cover operating elements for the support disposed and movable in the spaces between the support and the side walls and working top.

60 HOWELL G. EVANS.
